UNITED STATES PATENT OFFICE

LEE COCHRAN, OF ANDERSON, SOUTH CAROLINA

BURIAL VAULT

Application filed January 26, 1932. Serial No. 589,024.

My invention relates to improvements in burial vaults.

In accordance with my invention, I provide a burial vault formed of concrete or other plastic material, and having reinforcing means positively preventing the same from cracking and also serving to render the vault waterproof. The vault is preferably capable of being hermetically sealed.

10 In the accompanying drawings forming a part of this specification, and in which like numerals are employed to designate like parts throughout the same,

15 Figure 1 is a perspective view of a vault embodying my invention,

Figure 2 is a transverse section taken on line 2—2 of Figure 1,

20 Figure 3 is a detail transverse section taken on line 3—3 of Figure 1,

Figure 4 is a fragmentary perspective view of the reinforcing means,

Figure 5 is a plan view, partly diagrammatic, of the reinforcing fabric,

25 Figure 6 is a horizontal section through one end of the metal case and reinforcing fabric,

Figure 7 is a vertical section through one side of the metal case and reinforcing fabric, and

30 Figure 8 is a perspective view of a modified form of vault.

Referring first to Figures 1 to 4, inclusive, of the drawings, the numeral 10 designates the body portion of the vault, which is open at its top and closed at its bottom. This

35 body portion embodies a metal case 11, which may be formed of steel, iron, copper, lead, or any suitable metal. The metal case may also be treated so that it will not corrode. Highly satisfactory results are obtained by forming the case of steel, due to its strength and stiffness. This case is an integral structure.

40 The numeral 12 designates a reinforcing metal fabric. This fabric embodies longitudinal and transverse strands 13 and 14, and these strands cross at a right angle, affording rectangular openings or spaces. At all of their points of crossing these strands are rigidly attached to each other by welding, as shown more clearly at 15, in Figure 4. The 45 metal fabric embodies an outer bottom 16, ar-

ranged beneath the bottom of the case 11, and outer sides 17 and 18. These sides are foldable upon lines 17' and adapted to be arranged outwardly of the sides of the metal case, and then folded inwardly upon themselves, on lines 20, producing inner sides 21, arranged upon the inner surfaces of the sides of the metal case. The section 18 also carries an inner bottom 22, foldable along the line 23, whereby the bottom 22 is arranged upon the top of the bottom of the case 11. The free end of the inner bottom 22 is welded to the free end of the inner side 21, at each transverse strand 13. The reinforcing fabric also embodies end portions 24, including outer ends 25, which engage the outer sides of the ends of the case 11, by folding the same along lines 26. The portions 24 further embody inner ends 27, foldable along lines 28, so that the ends 27 will engage the inner surfaces of the ends of the metal case. The outer ends 25 are welded to the outer sides 17 and 18, at each longitudinal strand 13, and the inner ends are welded to the inner sides 21, at each longitudinal strand and, in addition, the ends of the inner ends 27 are welded to the ends of the inner bottom 22, at each longitudinal strand. By the several welded

50 joints, the reinforcing metal fabric, when applied to the case, becomes an integral structure, conforming to the shape of the same, and extending over the entire inner outer and inner surfaces of the same. The spacing elements 14', which occur near each corner of each rectangular space or opening of the fabric, engage with the case and retain the reinforcing fabric suitably spaced from the surfaces of the metal case. Each spacing element 14' is U-shaped and bent from the transverse strands 13 and projects laterally and inwardly beyond the strands. Each spacing element is directly rigidly attached to the case by welding, as shown at 29, in Figure 4. It is thus seen that the metal case and the reinforcing metal fabric are an integral structure, and the several connections between the fabric and the case are uniformly distributed throughout the entire surfaces of the case, and occur near each corner of the rectangular 55 spaces of the fabric.

50 60 65 70 75 80 85 90 95 100

The metal case 11, equipped with the metal reinforcing fabric, as described, is embedded in a concrete case or covering 30, formed of cast concrete. The metal case and reinforcing fabric have suitable mold elements arranged exteriorly and interiorly of the same to permit of the pouring of the concrete case or covering. This concrete covering completely encloses the case and reinforcing metal fabric and extends over all exterior and interior surfaces. The metal case is thus embedded within the concrete case or covering, and is securely attached or bonded to the same, the metal case, reinforcing fabric and concrete case or covering thus forming, in effect, an integral structure. The concrete case is preferably cast with an exterior horizontal flange 31.

As the top of the body portion 10 is open, the vault is provided with a cover 32. This cover includes a sheet metal lining 33, formed of steel, iron, or the like, preferably treated for preventing corroding. This cover lining is bent along longitudinal lines, to produce the desired transverse contour of the cover and includes ends 34, and vertical side portions 35. The cover lining 33 is provided with a reinforcing metal fabric 36, identical with the fabric 12. A section of this fabric is arranged upon the top or outer surface of the covering lining 33, and is bent inwardly over the longitudinal edges of the same and bent to conform to the shape of the inner surface of the lining, the free edges of the fabric being welded together at each of the transverse strands 14. The reinforcing fabric extends over the entire inner and outer surfaces of the cover lining. The spacing elements 14' retain the wire fabric 36 suitably spaced from the cover lining, and these spacing elements are directly rigidly attached to the cover lining by welding. The reinforcing fabric is, therefore, rigidly attached to the cover lining at substantially each corner of the rectangular spaces of the fabric. The cover lining 33, with the metal reinforcing fabric applied thereto, in the manner stated, now has the concrete case or covering 38 poured about the same, and when the concrete case or covering hardens, the metal cover lining 33 and reinforcing fabric will be embedded within the same. The concrete case or covering and the cover lining and reinforcing fabric constitute, in effect, an integral structure. The cover has a recess 39, for the reception of the top of the body portion 10, and depending flanges 40, to engage upon the flange 31, this arrangement affording a hermetical seal.

In Figure 8 I have shown a modified form of burial vault within which the body portion 41, corresponding to the body portion 10, is formed closed at its top and open at its bottom. The open bottom is closed by a cover element or bottom 42, corresponding to the bottom 32. The construction of these parts

remain substantially identical with those described in connection with the first form of my invention.

In view of the foregoing description, it will be obvious that I have provided a concrete vault having a metal reinforcing, affording the maximum strength and rigidity, and rendering the vault waterproof.

It is to be understood that the forms of my invention herewith shown and described are to be taken as the preferred example of the same, and that various changes in the shape, size and arrangement of parts may be resorted to without departing from the spirit of the invention or the scope of the subjoined claims.

Having thus described my invention, what I claim is:

1. A burial vault embodying a body portion comprising an integral metal case, a metal reinforcing fabric extending over the entire outer and inner surfaces of the metal case and over the free edges of the same, said reinforcing fabric embodying longitudinal and transverse strands which cross for producing polygonal openings, said fabric having spacing elements at the corners of each polygonal opening, portions of the reinforcing fabric being welded together and the spacing elements being welded to the metal case, the arrangement being such that the reinforcing fabric and metal case form in effect an integral structure, and a concrete case having the metal case and reinforcing metal fabric embedded therein.

2. A burial vault embodying a body portion comprising an integral metal case, a metal reinforcing fabric extending over the entire outer and inner surfaces of the metal case and over the free edges of the same, said fabric embodying longitudinal and transverse strands which cross for producing polygonal openings, certain of the strands being bent to form laterally extending spacing elements arranged near each corner of each polygonal opening, portions of the reinforcing fabric being welded together and the laterally extending spacing elements being welded to the metal case, and a concrete case having the metal case and reinforcing fabric embedded therein, the arrangement being such that the metal case, reinforcing fabric, and concrete case form in effect an integral structure.

3. A burial vault embodying a body portion comprising an integral metal case, a metal reinforcing fabric for coaction with the metal case including strands which cross each other for producing substantially rectangular openings, said fabric including an outer bottom, outer sides carried by the bottom and foldable over the edges of the metal case and carrying inner sides, one inner side carrying an inner bottom foldable upon such inner side, the inner bottom having its strands

at its free end welded to the corresponding strands of the other inner side, said fabric comprising outer ends carrying inner ends which are foldable over the edges of the ends 5 of the metal case, the strands of the outer ends being welded to the corresponding strands of the outer sides and the strands of the inner ends being welded to the corresponding strands of the inner sides and 10 the inner bottom, certain of the strands being bent inwardly for producing laterally projecting spacing elements, said spacing elements being arranged near all of the corners of each substantially rectangular opening, 15 the spacing elements being welded to the metal case, and a concrete case having the metal case and reinforcing fabric embedded therein, the arrangement being such, that the metal case, reinforcing fabric, and concrete 20 case form in effect an integral structure.

In testimony whereof, I affix my signature.
LEE COCHRAN.
